UNITED STATES PATENT OFFICE.

JAMES HOLMES, OF JAMESTOWN, NEW YORK.

KNOCKDOWN DESK.

SPECIFICATION forming part of Letters Patent No. 723,464, dated March 24, 1903.

Application filed October 2, 1902. Serial No. 125,642. (No model.)

To all whom it may concern:

Be it known that I, JAMES HOLMES, a citizen of the United States, residing at Jamestown, in the county of Chautauqua and State of New

5 York, have invented certain new and useful Improvements in Knockdown Desks; and I do hereby declare that the following is a full, clear, and exact description of the same, reference being had to the annexed drawings, 10 making a part of this specification, and to the letters of reference marked thereon.

The present invention has for its object to provide a knockdown desk in which the legs thereof may be readily attached and detached

15 from the body of the desk and when connected to the body of the desk the legs will be perfectly firm and rigid, as though originally built in the body, and the removal of the legs enabling the desk to be packed and crated 20 with economy of space and materially lessening the cost of shipment and with less liability of breakage, thereby presenting a knockdown desk that when set up will present the same outward appearance, strength, and durability of the desks in which the legs are 25 built in the body and not removable.

The invention consists in a knockdown desk constructed substantially as shown in the drawings and hereinafter described and 30 claimed.

Figure 1 of the drawings is a perspective view of a knockdown desk embodying my invention, showing the top and the drawer thereof partly broken away at the corners; Fig. 2, 35 a perspective view of one of the end sections of the body of the desk on an enlarged scale; Fig. 3, a perspective view showing the upper portion of the leg where it joins the body of the desk; Fig. 4, a similar view of one of the 40 rear legs; Fig. 5, a detail sectional view of the body of the desk, showing a portion of one of the rear legs and the means employed for detachably connecting the back section to the body.

45 The body of the desk is preferably constructed of the two end sections A, the top section B, the bottom section C, which forms the bottom of the desk, and the back section D, a suitable drawer being provided, as indicated at E.

The above elements comprise the desk-body,

to which are detachably connected the front legs F and the rear legs G, which legs may be of any suitable shape and either ornamental or plain, as found desirable.

55

The legs are formed with extensions a at their upper ends, and at the juncture of the leg with the extension is a supporting-shoulder b to support and sustain the corners of the desk-body when the legs are connected thereto, said legs being provided with suitable dowels c, adapted to engage the dowel-holes d in the end sections A at both the front and rear of the desk-body.

The extensions a of the legs F are formed 65 with inwardly-extending flanges e at right angle to the extension, so that when the legs are in place on the desk-body the flanges of the legs will embrace and cover the front edge of the end sections A, as shown in Fig. 1 of the 70 drawings.

The extensions to the front legs F are of a length equal to the height of the drawer-front, and the upper edge of the extension has a bevel o to correspond with the inclined edge 75 p of the two end sections A when the legs are in place on the desk-body. The extension a to the front legs, together with the flange e, overlaps the side of the end sections A and the front edge thereof, respectively, which 80 perfectly covers the front corner of the desk and not only forms a finish thereto, but materially strengthens that portion of the desk where the front legs join the body thereof and also holds the leg more firmly in place and 85 forms a rigid connection between the desk-body and leg.

The outer sides of the end sections A are provided with strengthening-strips f at the rear edge thereof, which strips also form continuations of the rear legs G when said legs are connected to the desk-body.

90 The legs G are made sufficiently short in length so that when removed from the desk both the front and rear legs may be securely wrapped and packed within the body of the desk.

95 The extensions a to the rear legs G are provided with flanges g, which overlap the lower ends of the strengthening-strips f to form an 100 overlapping joint between the two.

The extensions of both the front and rear

legs are formed with screw-holes *h i*, and the end sections of the desk-body are formed with screw-holes *j k*, which will be on line with the screw-holes in the leg extensions when said legs are in place on the desk-body, so that suitable screws *l* will engage the holes in the end sections and leg extensions. These screws serve a different purpose than the ordinary fastening-screw in that the screws draw the dowels tightly into the dowel-holes and also the inner side of the leg extensions tightly against the side of the end sections of the desk-body. Some means is absolutely necessary to obtain this end, and I have shown what I consider the simplest means in the form of a screw to draw the dowels and leg extensions to their place, although any means may be employed that will serve the purpose, there being a coaction between the screws or other means employed and the dowel-fastenings to form a perfectly secure and firm and rigid joint between the leg and the body of the desk. The screws, as will be seen, enter from the inside of the desk-body, thereby concealing every means of fastening the legs to the body when the drawer is in place, thereby having no appearance of the legs being detachable, but, on the contrary, have the appearance of being built in the body and not removable. The screws being connected from the inside of the desk-body and being so near the rear edge of the end sections, it is necessary in order to remove or replace the screws to first remove the back section *D* of the desk-body, so that access may be had to the heads of the screws by a screw-driver or other like tool and the same turned, which could not be done with the back section in place, as said section would be in the way of turning the screw-driver. It is therefore necessary to have the back section removable in order to remove or replace the rear legs of the desk, so as to allow sufficient room for turning the screw-driver.

45 To make a firm joint between the back section and the end sections of the desk-body the latter are formed with rabbets *m* upon their inner sides and at their rear edges, as shown in Fig. 2 of the drawings, the edges of the back section engaging the rabbets when said section is drawn up against the rabbets to form a tight and perfect joint. The lower end of rabbet *m* will expose sufficient of the supporting-shoulder *b* to sustain the lower edge of the back section *D*, as shown in Fig. 5 of the drawings, thereby giving additional advantage of the rabbeted edges of the end section of the desk-body. The back section *D* not being permanently attached to the desk-body by glue, nails, or other like means of fastening, but, on the contrary, designed wholly to be conveniently removed and replaced when circumstances require, it is necessary to provide some means of temporarily holding the back section in place that will not show from the outside of the desk-body. To attain this end, there is provided what is

considered the most simple means of detachably connecting the back section to the desk-body and that will draw the back section 70 tightly against the rabbeted edges of the end section, which means comprises the pivoted hooks *H I*, adapted to engage the staples or eyes *n*. Any desirable number of hooks may be used and are arranged in pairs, each one 75 of the hooks *H I* forming a pair, the hooks *H* being pivotally connected to the under side of the desk-bottom *C* and the hook *I* being similarly connected to the end section *A*, as shown in Fig. 5 of the drawings. The hooks 80 comprising each pair are arranged at right angles to each other, an equal number of hooks being connected to the desk-bottom and to the end sections, forming a perfect fastening for the back of the desk. 85

Having now fully described my invention, what I claim as new, and desire to secure by Letters Patent, is—

1. In a desk in which the end, front, top and bottom sections are permanently connected together, suitable legs detachably secured thereto, said legs having upwardly-projecting extensions to overlap the end sections of the desk-body and shoulders to support the corners thereof, and suitable dowels 90 upon the extensions to engage the end section from the outer sides thereof, and fastening means engaging the extensions of the legs from the inside of the desk-body to draw the extensions up against the end sections 95 thereof, and a detachable back whereby the same may be removed to obtain access to the interior of the desk-body from the rear thereof to remove or replace the fastening means in disconnecting or connecting the legs, substantially as and for the purpose set forth. 100

2. In a desk, the combination with the body thereof, having vertical strengthening-strips secured to the end sections of the body which also form a continuation of the rear 110 legs, of detachable legs having extensions formed with supporting-shoulders and overlapping flanges, the flanges upon the front legs overlapping the edges of the end section of the body and the flanges of the rear legs 115 overlapping the lower ends of the strengthening-strips, substantially as and for the purpose described.

3. In a desk, the combination with the body thereof and a removable back section 120 thereto, of detachable legs having extensions with supporting-shoulders, overlapping flanges, and dowels, and means for drawing the extensions against the end sections and the dowels into the dowel-holes of said sections, said means consisting of screws entering the end sections from the inner sides thereof and engaging the inner sides of the extensions of the legs, substantially as and for the purpose specified. 125

4. In a desk, the combination with the body thereof having the end sections of the body rabbeted at their rear edges, and suitable legs detachably connected to the body 130

and provided with supporting-shoulders, of
a detachable back section engaging the rab-
beted edges of the end sections and support-
ed by the shoulders upon the rear legs, and
5 suitable means for holding the back section
removably in place, substantially as and for
the purpose set forth.

In testimony that I claim the above I have
hereunto subscribed my name in the pres-
ence of two witnesses.

JAMES HOLMES.
